CLAIM

The ornamental design for a pinch clamp as shown and described.

DESCRIPTION

FIG. 1 is a left, rear, top perspective view of a pinch clamp showing the new design.

FIG. 2 is a top, front, right perspective view thereof.

FIG. 3 is a bottom, front, left perspective view thereof.

FIG. 4 is a bottom, rear, left perspective view thereof.

FIG. 5 is a right side elevation view thereof.

FIG. 6 is a left side elevation view thereof.

FIG. 7 is a front elevation view thereof.

FIG. 8 is a rear elevation view thereof.

FIG. 9 is a top plan view thereof.

FIG. 10 is a bottom plan view thereof; and,

FIG. 11 is a front, right, top perspective view of a cross section of FIG. 2.

1 Claim, 11 Drawing Sheets
